(57) **CLAIM**

We claim the ornamental design for a display screen with graphical user interface, as shown and described.

DESCRIPTION

FIG. 1 is a front view of a first embodiment of a display screen with graphical user interface of the present invention; and, FIG. 2 is a front view of a second embodiment of a display screen with graphical user interface of the present invention. The broken lines shown represent unclaimed subject matter and form no part of the claimed design.
